CANDELABRUM

Arthur F. Klingberg, McHenry, Ill., assignor to Bernard Edward Company, Chicago, Ill., a corporation of Illinois

Application September 27, 1952, Serial No. 21,620

Term of patent 7 years

(Cl. D48—2)

To all whom it may concern:

Be it known that I, Arthur F. Klingberg, a citizen of the United States and a resident of the city of McHenry, county of McHenry, State of Illinois, have invented a new, original, and ornamental Design for a Candelabrum, of which the following is a specification, reference being had to the accompanying drawing, forming a part thereof, in which:

Fig. 1 is a front elevational view of a candelabrum showing my new design;

Fig. 2 is a side elevational view of the same looking from the right of Fig. 1;

Fig. 3 is a top plan view.

Fig. 4 is a fragmentary elevational view taken substantially on line 4—4 of Figure 3.

I claim:

The ornamental design for a candelabrum, substantially as shown.

ARTHUR F. KLINGBERG.
